(57) **CLAIM**

The ornamental design for a surgical saddle, as shown and described.

DESCRIPTION

FIG. 1 is an isometric perspective of a surgical saddle showing my new design

FIG. 2 is a right side view thereof;

FIG. 3 is a front view thereof;

FIG. 4 is a back view thereof;

FIG. 5 is top view thereof; and,

FIG. 6 is a bottom view thereof.

The dashed lines depict portions of the surgical saddle that form no part of the claimed design. The dot-dash-dot broken lines in the drawings depict boundaries of the claimed design and form no part thereof.
